L. PICKERING AND J. LIGHTNER.

Car Bumper.

Patented June 28, 1836.

Daniel A. Pickering Jr. 9795X
and
John Lightner 6-28-1836
Letters Patent

The Schedule referred to in these Letters Patent, and
making part of the same, containing a description in the words of the said
Daniel A. Pickering, and John Lightner themselves of their Improvement
in the manner of attaching Rail Road Cars to the motive power.

To all people to whom these presents shall come: Daniel A. Pickering
and John Lightner both of Weston County of Suffolk and State of Massa-
chusetts, send greeting... Be it known, that we Daniel A. Pickering
and John Lightner have invented, made, constructed and applied to
use, a new and useful improvement in the manner of attaching Rail
Road Cars to the motive power wherein each Cart is attached in the
train by a particular spring, which we call the Independent Car Spring
providing advantages over all other modes of attaching the same as
the shaft is connected through the whole train by a stiff spring, thus
allowing the spring to act independently on each car to which applied
either in progress or sloping. The advantages which are specified at
first view over that mode by which the whole train is connected by one
spring that being made very stout and strong is ineffectual in most en-
counters. Wherewith is forwarded to the Patent Office a model, and two sets
of Drawings, by reference to which this Specification can be readily under-
stood.

Our Improvement is represented by a frame of wood which represents
the Cart to which the axles are attached, with a perch through the
center AA are the side pieces to which the axles are attached,
B is the perch, C is a shaft of iron sufficiently strong to sustain the train
of cars, extending the length of cars, secured in its place by clamps
made fast to the perch, in which it is movable, D is an elastic

6-28-1836

Spring of sufficient strength to sustain one Carr. E. a clasp having over and enclosing the Spring and made fast to the Shaft. A Bolt through the center of the Spring fastened to the side of the clasp, on which the spring is movable. & a Box or two separate pieces of cast iron or other material with an aperture in each side or piece to admit the Spring at its greatest tension; secured to the Perch serving for the shaft and Spring to work in of sufficient strength for a stop or stay. II II are clasps over the shaft secured to the perch in which the shaft moves. We claim as our invention the shaft, the manner it slides on the perch. The spring attached to it. We claim as an arrangement the clasp and bolt that sustains the spring, and the box or sides secured to the perch, operating as stops, in in the shaft and spring work. For which we pray that the combination may be secured to us according to law.

I testimony that the foregoing is a true specification of our said invention, We have hereunto set our hand this 29 day of April in the year of our Lord One thousand eight hundred and thirty six
